UNITED STATES PATENT OFFICE.

WILLIAM H. HOOKER, OF JERSEY CITY, NEW JERSEY.

EJECTOR.

SPECIFICATION forming part of Letters Patent No. 511,079, dated December 19, 1893.

Application filed October 6, 1893. Serial No. 487,322. (No model.)

To all whom it may concern:

Be it known that I, WILLIAM H. HOOKER, of Jersey City, in the county of Hudson and State of New Jersey, have invented a new and useful Improvement in Ejectors, of which the following is a specification.

My invention relates to an improvement in ejectors in which the nozzle for ejecting the actuating fluid into the barrel of the ejector is made capable of being adjusted into and out of the barrel at pleasure and during the operation of the ejector without the necessity of uncoupling either the nozzle from the supply pipe or the nozzle from the ejector barrel.

A practical embodiment of my invention is represented in the accompanying drawings, in which—

Figure 1 represents the ejector in longitudinal section and Fig. 2 represents a transverse section through line α, α of Fig. 1.

The barrel of the ejector is denoted by A and is provided at its inlet end with an enlarged chamber a , as is usual, and at its opposite end with an expanded mouth a' . The fluid to be ejected enters the chamber a through a suitable opening a^2 .

The nozzle for the admission of the actuating fluid is denoted by B. It enters the chamber a of the barrel A through an opening a^3 in a direction substantially at right angles to the opening a^2 through which the fluid to be ejected enters, and projects when in operation more or less completely across the chamber a with its outlet end approaching the contracted portion of the barrel A. The fit of the nozzle B within the opening a^3 is intended to be as snug as is consistent with the longitudinally sliding movement of the nozzle B. Surrounding the opening a^3 there is a tubular boss a^4 projecting outwardly from the wall of the chamber a and having an interior bore larger than the opening a^3 . The interior of the tubular boss a^4 is screw threaded and a sleeve or bushing C, externally screw threaded, is adapted to register with and screw into the boss a^4 . The sleeve

or bushing C is provided with an interior bore adapted to snugly fit the exterior of the nozzle B but, at the same time, permit the said nozzle B to slide longitudinally therein.

The nozzle B is provided along a portion of its exterior outside of the sleeve or bushing C, with a screw thread b . A skeleton adjusting nut D is fitted at one end d with an interior screw thread, adapted to engage the screw thread b on the nozzle and at its opposite end is provided with an annular inwardly extending ring d' constructed to loosely embrace the exterior of the sleeve or bushing C in proximity to the outer end of the tubular boss a^4 . The nut D is locked in operative position by means of a nut E constructed to engage the reduced, screw threaded, outer end c of the sleeve or bushing C. The construction is such that when the nut E is screwed onto the end of the sleeve or bushing C, the inner side of the nut will loosely engage the outer side of the inwardly projecting ring d' on the skeleton nut D so as to permit the latter to rotate freely between the said nut E and the outer end of the tubular boss a^4 . The nozzle B is further conveniently provided with an annular projection b' a short distance from its outer end, its exterior from its projection b' to its extreme end being screw threaded for the purpose of conveniently attaching thereto a supply pipe.

The operation of the device is as follows:— Whenever it is desired to vary the effective force of the actuating fluid under a given pressure, the nozzle B may be advanced toward or withdrawn from the contracted portion of the barrel A by simply turning the skeleton nut D in the one direction or the other, its engagement with the screw thread b upon the nozzle serving to move the latter longitudinally without disturbing its connection, either with the supply pipe or with the barrel of the ejector.

By the above described arrangement, I am enabled to utilize the actuating fluid to the greatest possible advantage by varying the

position of the nozzle to correspond with the varying loads or depths from which the fluid to be ejected is to be drawn.

What I claim is—

5 The combination with the ejector barrel and a nozzle having a longitudinally sliding movement into and out of the barrel, of a sleeve or bushing engaged with the barrel and surrounding the nozzle, an adjusting nut

engaged with the nozzle and surrounding a portion of said bushing or sleeve and means for locking the said adjusting nut in its position on the said bushing or sleeve, substantially as set forth.

WILLIAM H. HOOKER.
